UNITED STATES PATENT OFFICE

111,507

DESIGN FOR A POWER LAWN MOWER OR SIMILAR ARTICLE

Allyn R. Cooper, Marshalltown, Iowa, assignor to
Cooper Manufacturing Company, Marshall-
town, Iowa, a corporation of Iowa

Application April 25, 1938, Serial No. 76,744

Term of patent 7 years

To all whom it may concern:

Be it known that I, Allyn R. Cooper, a citizen of the United States, and a resident of Marshalltown, in the county of Marshall, and State of Iowa, have invented a certain new, original, and ornamental Design for a Power Lawn Mower or Similar Article, of which the following is a specification, reference being had to the accompanying drawing, forming part thereof:

Figure 1 is a perspective view of a power lawn mower or similar article showing my new design; and

Figure 2 is a similar perspective view taken from the opposite side of the mower with a portion of the handle shown in dotted lines broken away for convenience of illustration.

The dominant features of my design reside in the portions shown in full lines on the drawing.

I claim:

The ornamental design for a power lawn mower or similar article, substantially as shown and described.

ALLYN R. COOPER.
